UNITED STATES PATENT OFFICE.

JAMES P. SMITH, OF INDIAN ROCK, VIRGINIA, ASSIGNOR OF ONE-HALF TO FRANK Z. HYDE.

RAILWAY TIE AND TIE PLATE.

Application filed August 15, 1924. Serial No. 732,233.

To all whom it may concern:

Be it known that I, JAMES P. SMITH, a citizen of the United States, residing at Indian Rock, in the county of Botetourt and State of Virginia, have invented certain new and useful Improvements in Railway Ties and Tie Plates, of which the following is a specification.

The object of this invention is to provide a metallic railway tie of cheap and simple construction with a reversible tie plate for compensating for the wear on one side of the rail.

With other objects in view, as will be more fully set forth as the following description proceeds, reference will be had to the accompanying drawing which forms a part of this specification and wherein like numerals of reference are used to designate corresponding parts throughout the several views, in which:—

Fig. 1 is a top plan view of the complete invention,

Fig. 2 is a view in side elevation thereof, Fig. 3 is an enlarged top plan view in detail of a fragment of Fig. 1,

Fig. 4 is a vertical longitudinal sectional view of the portion illustrated in Fig. 3, and

Fig. 5 is a vertical transverse sectional view taken on line 5—5 of Fig. 2.

In the drawing, reference numeral 1 designates a tubular metallic railway tie, the same being formed into a tube by drawing, rolling or otherwise, and with or without a seam, and such seam, if present, being welded or not. For the purpose of drainage and ventilation, the tubular tie may be, and preferably is, provided with perforations 2 in its side or other wall or walls. Within each end of the tubular tie is located a wooden or composition spiking block 3, and each of these blocks extends preferably only from the outer end of the tie to a point well beyond the plane of the rail 4, and to facilitate removal of these blocks from within the tubular tie, the ends of the tie are notched as at 5 so as to expose the outer ends of the spiking blocks so that they may be grasped by pulling tongs or the like and thereby extracted from the tie.

The upper wall of the tie is cut out to provide a pocket 6 to receive a reversible tie plate 7. Both are given the same contour,

and in the drawing, this is shown to be rectangular. On each side of the pocket, the upper wall of the tie is again cut way as at 8, thereby exposing the spiking block 3 and an edge 9 of each side wall of the metallic tie. The pocket 8 is slightly wider than the width of the rail base so that the rail 4 never comes into contact with the top wall of the tie, unless wear of the spiking block 3 by the tie plate 7 becomes excessive.

By reference to Fig. 3, it will be observed that the distance from the shoulder 10 of the rail seat of the tie plate 7 to the left hand edge of the tie plate is shorter than the distance from the other shoulder 11 to the right hand end of the tie plate. In new installations, the tie plates are set with these shorter portions or ends 12 toward the outer ends of the tie 1, and with the longer ends 14 between the positions occupied by the rails. The rails 4 are then placed in the seats of the tie plates 7 and the spikes 15 driven through apertures 16 in the tie plates and into the spiking blocks 3, the heads of the spikes engaging and securing the rails 4 in the usual manner.

By reference to Fig. 3, it will be observed that the spiking holes 16 at one end coincide with those at the other end, so that when a rail becomes worn on one side as to increase the gauge of the rails to a dangerous degree, and this is compensated for by reversing the tie plates, the spikes will enter the same spike holes previously formed in the spiking blocks 3. When the tie plates are reversed, the longer ends 14 of the tie plates will occupy the positions previously occupied by the shorter ends 12, so that the long end 14 is moved from the worn side of the rail to the unworn side, thereby moving the worn side of the rail toward the center of the tie and in that way compensating for the wear and restoring the rails to proper gauge. The new positions then occupied by the shoulders 10 and 11 are illustrated by dotted lines in Fig. 3, and the center of the rail moves from the first position indicated by line 16 to the second position indicated by line 17. In Fig. 4, it will be observed that the tie plate ends are of a greater thickness than the top wall of the tie so that in case of excessive wear on the spiking block, the tie plates, because of the thickness of their ends, will not slip between the spiking

block and the under face of the top tie wall, but the ends of these tie plates will at all times abut and engage with the walls of the pockets 6.

5 Of course it is to be understood that other forms of tie plates may be substituted for the type herein illustrated, or the adopted ones herein may be modified, and further that changes and modification may also be 10 made in the tie and spiking blocks, so long as such changes come within the scope of the claim or claims to be obtained.

What is claimed:—

1. A tubular railway tie, a spiking block 15 therein, a tie plate resting on said block and being reversible to change the position of the rail.

2. A tubular railway tie, a spiking block 20 therein, a tie plate resting on said block and being reversible to change the position of the rail, and spikes passing through said tie plates and into the spiking block, the tie being formed with a pocket to receive the tie plate in both of its positions.

25 3. A tubular railway tie, a spiking block therein, a tie plate resting on said block and being reversible to change the position of the rail, and rail securing spikes passing through said tie plates and into the same.

holes in the spiking blocks for both positions of the tie plates. 30

4. A tubular metallic railway tie, a spiking block therein, a tie plate resting on said block and being reversible to change the position of the rail, rail securing spikes passing through said tie plates and into the same 35 holes in the spiking blocks for both positions of the tie plate, said tie plate being snugly received in both of its positions in an opening formed in the upper wall of 40 the tie.

5. A device of the nature described in claim 5, further characterized by the tie plate being of a greater thickness than the upper wall of the tie to avoid its entering 45 between said upper tie wall and the spiking block when the latter becomes worn.

6. A tie plate provided with a rail seat having shoulders on each side of said seat to engage the sides of the rail base, the distance from one of said shoulders to the adjacent end of the tie plate being less than that between the other shoulder and its adjacent end of the tie plate, and spiking openings at both ends of the tie plate equidistant from such ends. 50 55

In testimony whereof I affix my signature:

JAMES P. SMITH.
